UNITED STATES PATENT OFFICE.

ALEXANDER WINTON, OF CLEVELAND, OHIO.

GASOLENE-CARBURETER.

No. 869,675.

Specification of Letters Patent.

Patented Oct. 29, 1907.

Application filed November 10, 1904. Serial No. 232,167.

To all whom it may concern:

Be it known that I, ALEXANDER WINTON, a citizen of the United States, residing at Cleveland, in the county of Cuyahoga and State of Ohio, have invented 5 certain new and useful Improvements in Gasolene-Carbureters, of which the following is a specification, reference being had therein to the accompanying drawing.

This invention relates to improvements in gasolene 10 carbureters, and is for use in connection with explosive engines, the object of which is to provide means for adjusting the air supply automatically by the suction action of the engine, and also manually independently of the action of the engine.

15 The accompanying drawings illustrate a sectional view through the improved carbureter.

The gasolene is fed to the carbureter through a pipe 24 to a passage 25 which extends into the air passage-way 26, and this passage-way 25 has a restricted outlet 20 27 which is controlled by a valve 28 extending to the outside of the carbureter, and provided with an operating head 29 by means of which the valve is adjusted. A lock-nut 30 serves to hold the valve 28 to its adjusted position.

25 Air is admitted to the carbureter through the inlet 34 which is preferably provided with a suitable gauze covering 35. Located in the passage 34 is a partition 36, and this partition is formed with an outer series of perforations 37, and an inner series of perforations 88, 30 the combined area of these perforations being in excess of the required area to provide a maximum amount of air for the motor. Exending inward from this partition 36 is an annular member 39, the inner face of which is made conical as shown, the smallest diameter of the cone surface being at the outer end of said member. The air passages 37 in the partition 36 are located at a point outside of the said member 39, while the air passages 38 are at a point to communicate with the interior of said member.

40 Located within the cone-shaped member 39 is a diaphragm 40, which serves to throttle the passage of the air through the openings 38. This diaphragm is held in the position shown by means of a spiral spring 41, the diaphragm and the spring being supported by a 45 suitable stem 43 which in turn is attached to a web 44. As shown, this diaphragm is a fairly close fit to the interior of the small end of the cone-shaped member 39, and hence serves to throttle or control the passage of the air through the openings 38 to the air passage 26 of 50 the carbureter. Formed in the diaphragm 40 is a series of small openings (about three in number) 42, so that a certain volume of air will pass through it before it is lifted and moved inward under the suction of the engine piston.

55 The inner or enlarged end of the cone-shaped member 39 is so constructed that it will coöperate with the

member 45 to limit the amount of air which will pass around the said member. This member 39 is carried by a longitudinally adjustable casting or sleeve 46 which screws around the end of the member 45 as shown 60 at 47 to accomplish the adjusting of the inner end 48 of the member 39 in respect to the end of the member 45, and is clamped in this position by means of a bolt 49 passing through perforated lugs 50.

Below the gasolene inlet 27 the carbureter is provided with a plurality of screens 51 placed within a chamber 52, and this chamber has at its lower end a passage 53 which communicates with the inlet of the engine or engines to be supplied with the explosive mixture. The engine or the said inlet are not here 70 shown, as they form no part of the present invention, and are not essential to a full understanding thereof.

In operation, the inner end of the member 39 is so adjusted as to provide the maximum area around its inner end for the passage of air, above which maximum area the diaphragm 40 is acted upon by the suction of the engine for providing or allowing an increased amount of air to pass to the carbureter through the interior of the member 39. When the suction of the engine is such that more air will be required than will pass around the cone-shaped member 39 and through the small openings in the diaphragm 40, then the diaphragm, under the influence of the suction is drawn inward within the cone-shaped member to the extent required to admit the additional amount of air necessary for the requirements of the engine. The air, after passing through these controlling members, enters the passage 26 and passes by the gasolene inlet or aspirating nozzle 27, and thence through a restricted passage-way 55 to and through the series of mixing screens 51 90 to the lower end of the chamber 52, and from this chamber to the inlet of the engine.

It is desirable to maintain the temperature of the chamber 51 at a substantially constant warm temperature, and this is accomplished by providing the chamber with a water-jacket 56 which may be placed in communication with the water-cooling system of the engine.

From the foregoing description, it will be observed that the passage ways 37 are in effect main passage-ways for the air, and the passage ways 38 are auxiliary passage-ways, and for the convenience of generic expressions, these passage-ways will be so designated in the claims.

Having thus described my invention, what I claim 105 and desire to secure by Letters Patent, is:—

1. An improved carbureter, comprising a mixing chamber, gasolene and air inlet passages in communication therewith, the air inlet passage having an annular member therein constructed to form a main air passage-way 100 theraround, auxiliary passage-ways in communication with the interior of the annular member, and a member normally obstructing the passing of air through the

auxiliary passage and adapted to be moved away from said passages under the influence of the engine, for the purpose described.

2. An improved carbureter comprising a mixing chamber having gasoline and air passages in communication therewith, the air passage having an adjustable annular member around which is formed a main air passage-way, auxiliary passages in communication with the interior of the annular member, and means located within the annular member for controlling the passage of the air through the auxiliary passage-ways.

3. An improved carbureter including a mixing chamber having gasoline and air inlet passages in communication therewith, an annular member within the air passage-way and constructed to form a main air passage therearound, auxiliary air passages in communication with the interior of the annular member, and means controlling the passage of air through the auxiliary passage-ways.

4. An improved carbureter comprising a mixing chamber having gasoline and air inlet passages in communication therewith, the air inlet passage having an annular member therein and constructed to form a main air passage therearound, the interior wall of the annular member being cone-shaped in cross-section, the cone diverging inwardly, auxiliary air passages in communication with the interior of the annular member, and an inwardly-movable diaphragm within the annular member and adapted to obstruct the passage of air through the auxiliary passages, the diaphragm adapted to be moved inward longitudinally the annular member by the suction of the engine. 20 25 30

In testimony whereof I affix my signature in presence of two witnesses.

ALEXANDER WINTON.
